US00D454202S

(12) **United States Design Patent** (10) Patent No.: **US D454,202 S**
Pham et al. (45) Date of Patent: ** Mar. 5, 2002

(54) **MULTI-WELL PLATFORM**

(75) Inventors: **Andrew A. Pham**, Del Mar; **Peter J. Coassini**, Encinitas; **Alec Tate Harootunian**, Del Mar; **Peter N. Pham**, San Diego, all of CA (US)

(73) Assignee: **Aurora Biosciences Corporation**, San Diego, CA (US)

(**) Term: **14 Years**

(21) Appl. No.: **29/081,976**

(22) Filed: **Jan. 12, 1998**

(51) LOC (7) Cl. **24-02**

(52) U.S. Cl. **D24/230**; D24/216; D24/227

(58) Field of Search D24/224, 226, D24/230, 216; 422/102, 104, 101; 435/288.4, 305.1, 305.2, 305.3, 305.4; D25/150, 152

Assistant Examiner—I Simmons

(74) Attorney, Agent, or Firm—Gray Cary Ware & Freidenrich LLP; Lisa A. Haile

(57) **CLAIM**

The ornamental design for a multi-well platform, as shown.

DESCRIPTION

FIG. 1: is a top plan view of a multi-well platform showing our new design,
FIG. 2: is a bottom plan view thereof,
FIG. 3: is a left elevation view thereof,
FIG. 4: is a right elevation view thereof,
FIG. 5: is a front elevation view thereof,
FIG. 6: is a back elevation view thereof; and,
FIG. 7: is a top, front, and right perspective view thereof.

1 Claim, 3 Drawing Sheets
